PUTTING GAME

Philip A. Streich, Oshkosh, Wis.

Application April 6, 1936, Serial No. 72,844

1 Claim. (Cl. 273—32)

This invention relates to improvements in putting games.

Heretofore games similar to golf have been marketed for lawn use, and these games have involved the use of holes toward which an ordinary golf ball is directed by a golf club. The holes are usually so positioned as to provide a putting course embodying nine or more holes, and the scoring is identical to that used in the regular golf game.

It is an object of the present invention to provide a putting game, preferably for lawn use, which is a distinct variation from the game as usually played, due to the fact that equipment of a special form is employed, thereby changing the manner of playing and the method of scoring.

A more specific object of the invention is to provide a putting game wherein the hole structure comprises a main opening toward which the ball is directed, and auxiliary openings or holes within the main opening, the main opening being so formed as to ultimately direct the ball into one of the auxiliary openings.

A further object of the invention is to provide a putting game embodying a hole structure as above described wherein the auxiliary openings have different values for scoring purposes.

A still further object of the invention is to provide a game embodying a hole structure as above described which eliminates the necessity of digging holes in the lawn and thereby disfiguring the same, there being novel means for removably anchoring the hole structure in proper position to prevent accidental displacement thereof.

A more specific object of the invention is to provide a game including a hole structure wherein the marking flag is employed for removably anchoring the hole structure in position on the lawn.

With the above and other objects in view, the invention consists of the improved putting game and all its parts and combinations as set forth in the claim and all equivalents thereof.

In the accompanying drawing illustrating one complete embodiment of the preferred form of the invention:

Fig. 1 is a perspective view showing a player holding a mallet of the type used in the improved game, and showing a ball being directed toward one of the improved hole structures;

Fig. 2 is a plan view on an enlarged scale of the improved hole structure; and

Fig. 3 is a vertical sectional view through the hole structure showing the means for anchoring the same in position.

Referring more particularly to the drawing, the numeral 5 designates a central cup shaped portion forming the main opening, and the numeral 6 designates a circular rim surrounding the cup shaped portion 5 and forming an inclined runway accessible from all sides, over which a ball 7 may pass as it is being directed toward the main opening 5. The hole structure is preferably formed of metal and is preferably stamped in one piece so that the inclined rim is integral with the upper edge of the cup portion.

In the center of the cup portion 5 is a substantially conical projection 8 having an opening 9 extending through its tip. The standard 10 of a flag 11 is adapted to have its pointed end 12 extending through the hole 9 and into the ground to thereby anchor the hole structure in proper position to prevent accidental displacement thereof. Thus the same member which is used as a standard for the marking flag 20 11 serves the purpose of anchoring the hole structure in position.

Surrounding the conical projection 8 are a plurality of openings 13, 14 and 15, preferably three in number, which form auxiliary holes. 25 These holes are of such size as to be capable of trapping the ball 7 when the latter rolls therein.

The main cup-shaped opening 5 has its bottom suitably dished as at 16 to direct the ball toward the center. When a ball falls into the main hole 5 it may in rolling toward the center thereof drop directly into one of the auxiliary holes 13, 14 or 15. Sometimes, however, it will pass through one of the spaces 17 between the auxiliary holes and strike the conical projection 8. The sloping sides of this projection, however, are such that the ball will immediately roll back to eventually fall into one of the auxiliary openings 13, 14 or 15. Thus the entire cup structure 5 is shaped to insure the ball ultimately reposing in one of the auxiliary holes 13, 14 or 15.

The game may be played in various ways. However, it is preferred to properly position nine or more of the holes in different locations so as to provide a putting course, the holes being suitably anchored in position by the standards of the marking flags, as heretofore described, and these marking flags may bear numerals indicating the order in which the holes are to be played. 50 It is preferred that the player use a mallet 18 which is somewhat similar to a croquet mallet, but which has a somewhat smaller head 19, preferably of streamlined shape provided with an end impact surface 20. The handle 21 is pref- 55

erably set into the head at an incline. The game can, of course, be played with an ordinary golf club and golf ball, but by using a mallet somewhat similar to a croquet mallet, older people who are not familiar with the golf method of stroking a ball, may be able to play the game more readily. For this same reason the ball is 10 preferably somewhat larger than a golf ball, but smaller than the usual croquet ball. This ball may be made of wood, hard rubber, or any other suitable material.

The game may be so played that the person taking the fewest strokes to go around the course is the winner. However, in this connection the improved equipment provides for considerable added interest over the ordinary golf method of scoring. The player cannot tell into which of the auxiliary holes 13, 14 or 15 the ball will ultimately rest. If it falls into the opening 13, one stroke may be deducted from the player's score. If it falls into the opening 14, one stroke may be added to the player's score, and if it falls into the opening 15 marked normal, the conventional scoring is employed. The holes may, of course, be marked in various other manners, the main idea being to attach different values to the different auxiliary holes. Due to this interesting feature in the scoring, a very entertaining game can be played with but a single hole, but it is, of course, better to lay out a complete course. In addition various hazards may be provided in advance of the hole structures to make low scoring more difficult.

While the game is more particularly adapted 35 for outdoor or lawn use, it may of course be

played in the parlour on a carpet. When so played the marking flags are not used, or the holes may be marked in some other manner.

Although only one form of the invention has been shown and described, it is obvious that various changes and modifications may be made without departing from the spirit of the invention, and all of such changes are contemplated as may come within the scope of the claim.

What I claim is:

A hole structure for a putting game comprising a cup-shaped body portion, the bottom of which is adapted to rest on a playing surface, an annular rim in connection with the upper peripheral edge of said cup-shaped body, said rim being inclined downwardly into contact with the playing surface to form an annular pathway for directing a moving ball from the playing surface up into the cup-shaped body, the bottom of said cup-shaped body having a central projection 20 formed with a hole in its tip, and there being auxiliary openings in said bottom surrounding said projection into one of which a ball is adapted to be directed, said auxiliary openings having different values for scoring purposes, a stake extending through said hole in the tip of the projection and into the playing surface to removably anchor the structure in position, said central projection being formed with sloping sides to direct the ball away from the stake and into 30 one of the auxiliary openings, the upper end of said anchoring stake projecting substantially above the cup, and a marking flag carried by the upper end of said anchoring stake.
